1 1/2

Fig. 1 is a perspective view showing one side and the front of a hydraulic precision index and pierce machine, showing my new design.

Fig. 2 is a perspective view showing the other side and the front thereof.

Fig. 3 is a plan view thereof.

Fig. 4 is a rear perspective view taken diametrically opposite Fig. 2.

The dominant features of my design reside in the portions shown in full lines.

I claim:

The ornamental design for a hydraulic precision index and pierce machine, substantially as shown and described.
